STEAM BATH FURNACE

Filed June 26, 1929

UNITED STATES PATENT OFFICE

JOHN G. HULME, OF CHISHOLM, MINNESOTA

STEAM BATH FURNACE

Application filed June 26, 1929. Serial No. 373,843.

My invention relates to steam bath furnaces and an object of the same is to provide a portable structure which may be placed in the bathroom of a dwelling or other room 5 for the purpose of generating steam therein.

Another object of the invention is to provide a steam bath apparatus consisting of a casing for the reception of stones or other heat retaining objects to be heated by a heating medium within the casing, and means for discharging water onto the heated stones 10 to produce a vapor or steam.

With the preceding and other objects and advantages in mind the invention consists 15 in the novel combination of elements, constructions and arrangements of parts and operations to be hereinafter more fully described, claimed and illustrated in the accompanying drawings, wherein:

20 Figure 1 is a perspective of the invention; Fig. 2 is a vertical sectional view of the same;

Fig. 3 is a vertical section taken on line 3—3 of Fig. 2;

25 Fig. 4 is a horizontal section taken on line 4—4 of Fig. 2.

Referring to the invention in detail a substantially rectangular casing 5 formed of sheet metal is provided. The upper end of 30 the casing is provided with a hood or top 6 which is hinged as at 7. The casing may be of various shapes and suitably ornamented.

In order to hold the hood or cover in 35 raised position a resilient latch bar 8 is provided and has one end secured to the upper wall of the casing and its opposite end extending through a slot 9 in the hood or cover. A bevelled projection or keeper 10 is formed on the inner face of the latch bar adjacent its forward end so that upon raising of the cover to normal position the keeper passes into the slot 9 and engages one of the walls of the latter.

A sheet metal fire box 11 is arranged in 45 the casing and extends the entire length thereof and has its side and rear end walls spaced from the casing. A suitable grate 12 is supported horizontally within the fire box, access to which is had by means of a hinged door 13 provided in the forward end

wall of the casing. In order to conduct the gases from the fire box a vertically extending flue 14 extends from the upper wall of the fire box through the upper wall of the casing and in practice is adapted to be connected to a chimney. The flue 14 communicates with a horizontally extending branch flue 15 arranged in the casing and which communicates with an outlet opening 16 in the upper wall of the fire box. The spaces 50 between the side and rear end walls of the casing and fire box and the upper portion of the casing are filled with rocks, or other vaporizing medium designated at 17. The objects 17 are heated by the products of combustion passing through the flues and fire contained in the fire box. With the objects 55 17 thus heated water coming in contact therewith will be instantly vaporized.

For the purpose of supplying water to the 60 objects 17 a horizontally extending perforated pipe 18 extends transversely of the casing above the objects and is provided with an upstanding funnel 19 at its outer end, the latter being disposed laterally of the casing so that when water is poured therein 65 it will be discharged onto the rocks where it is instantly vaporized.

In practice the hood is closed until sufficient heat has been created within the casing to form vapor. After sufficient heat has been attained the hood is raised and when water is applied on the vaporizing medium the vapor will rise therefrom and into the room in which the device is arranged. 70

What is claimed is:

1. In a vapor bath generator, the combination of a shell defining a fire box, a casing enclosing said fire box and in spaced relation thereto, a flue in communication with an upper portion of said fire box and extending in a plane horizontal therewith, a vertically disposed flue in communication with said first named flue and in spaced relation to said casing, heat retaining objects positioned within the space defined by said casing, fire box and flues, means for spraying a liquid on said heat storing means for generation of a vapor, said casing having an opening in its top extending over a major portion 80

tion thereof, and a hinged hood for closing said opening.

2. In a vapor bath generator, the combination of a shell defining a fire box, an open ended casing enclosing said fire box and in spaced relation thereto, a flue in communication with an upper portion of said fire box and extending in a plane horizontal therewith, a vertically disposed flue in communication with said first named flue and in spaced relation to said casing, heat retaining objects positioned within the space defined by said casing, fire box and flues, a closure for said open ended casing comprising a portion rigidly secured to said casing and having an aperture for accommodation of said vertically disposed flue and a hood member hingedly mounted to said rigid member, and means carried by said rigid member for spraying a liquid on said heat storing means for generation of a vapor.

JOHN G. HULME.
